UNITED STATES PATENT OFFICE

HANS LUCE, OF SOMMERDA, THURINGIA, GERMANY, ASSIGNOR TO FIRM RHEINISCHE METALLWAAREN- UND MASCHINENFABRIK SÖMMERDA AKTIENGESELLSCHAFT, OF SOMMERDA, GERMANY, A CORPORATION OF GERMANY

TYPEWRITING AND SIMILAR MACHINE

Application filed September 24, 1929, Serial No. 394,812, and in Germany September 28, 1928.

This invention relates to typewriting and similar machines and has more particularly reference to the means for coupling the platen with the line-spacing wheel.

The mechanisms hitherto known and used for connecting and disconnecting the platen with the line-spacing wheel in type-writers and similar machines are throughout of a very complicated construction, they require both comparatively numerous gear parts and a very high accuracy in the manufacture of the coupling members and the transmission members inserted between the coupling members and the manipulative handle or knob. Therefore the manufacturing costs of coupling mechanisms of this type and those of the appurtenant parts of the machine itself generally are very high when compared with the total manufacturing costs of a typewriter or similar machine.

The instant invention has for its object to provide a new coupling mechanism for the platen and the line-spacing wheel which is remarkable for the very simple construction of its parts and of those of the machine that co-operate therewith, and for its very low manufacturing costs. In the construction according to the invention a very slight rotation of a bolt about its longitudinal axis causes the coupling between the platen and the line-spacing wheel and, inversely, an equal slight backward rotation causes disconnection and return to initial position of these parts, the bolt being lodged in a bore provided in the appurtenant end cap of the platen and extending along a diameter or a chord therein, the cap being rigidly connected to the platen.

The simplest embodiment of this idea of invention is obtained by using the front surfaces of this bolt itself as locking means or coupling members. In such an embodiment the front surfaces or a portion thereof of the bolt when in releasing position lies flush with the cylindrical bearing surface provided on the hub of the platen cap for the line-spacing wheel, or a little below this surface. The front surfaces of the bolt or the bolt itself or both in co-operation are so designed that a slight turning motion of the bolt

about its axis causes an outward motion of its front surfaces which is sufficient to bring them into contact with the inner or race surface of the line-spacing wheel and thus to produce a friction between the hub of the platen cap and the wheel which friction causes a reliable coupling effect to be produced between these parts. In this embodiment one sole bolt will be sufficient which is lodged in the hub of the platen cap and extends along a diameter thereof. One may however provide two such bolts in parallel to a diameter in the vicinity of the center or the edge of the hub. This single bolt or these two parallel twin bolts may be subdivided so as to form two halves. The bolts may form smooth cylindrical stems lodged in cylindrical bores of the hub of the platen cap or in certain cases they may engage their bores by means of screw threads.

In order that the invention can be more easily understood, some preferred embodiments of the same are illustrated by way of example in the accompanying drawings in

Figure 1 is a longitudinal section through the platen of a typewriter fitted with the arrangement according to the invention.

Figure 2 is a cross section through the platen locking at the platen cap that encloses the coupling members.

Figure 3 shows a detail of the embodiment shown in Figures 1 and 2.

Figure 4 shows the parts to be seen in Figure 3 with one part in another position.

Figure 5 is a view similar to Figure 2 and shows a modified form of the coupling mechanism.

Figure 6 is a sectional side view thereof.

Figure 7 is a view similar to Figure 2 and shows a third embodiment.

Figure 8 is a sectional side view thereof, and

Figures 9 to 12 are details of further embodiments of the invention.

In all embodiments shown the line-spacing wheel denoted by *a* is loosely mounted on a corresponding cylindrical race surface of the hub of the platen cap *b*, which is rigidly connected to the platen proper. A rotation of

the hub of cap *b* together with the platen proper relatively to the line-spacing wheel *a* and inversely is possible as long as the coupling is out of operation. With the coupling thrown in, both said parts are in rigid mutual connection so that one of the parts when revolving carries with it the other part.

Referring now to the embodiment illustrated in Figures 1 and 2, the hub portion of cap *b* is provided with a cylindrical bore extending diametrically therein. In this bore is lodged so as to tightly fit but easily be turned therein the cylindrical coupling bolt *c*. In manufacturing, this bolt *c* is inserted in the bore when still of unfinished length, the race face of hub *b* likewise not being finished at this stage, and is fixed provisionally therein. Then the total race face that means inclusively of the end surfaces of bolt *c*, is turned on the lathe and ground to finished diameter. In this condition the end surface of bolt *c* forms a portion of the cylindrical race surface of the hub *b* of the platen cap, and in this mutual position of bolt *c* and hub *b* the line-spacing wheel can loosely rotate on the latter. In Figures 3 and 4 the hub *b* of the platen cap of Figures 1 and 2 is illustrated on an enlarged scale together with the coupling bolt *c* lodged therein. Figure 3 shows the initial position that is the mutual position of the parts in which the line-spacing wheel and the platen cap are out of connection. When now bolt *c* is turned about its longitudinal axis, then its cylindrical end surfaces do no longer lie flush with the bearing surface of hub *b*. If this angular rotation of bolt *c* would amount to 90 degrees, then the cylindrical end surface would be normal to its initial position, in which their ends would project beyond the bearing surface of hub *b*, as clearly to be seen in Figure 4. This 90 degrees rotation however is not required in practice, but only a fraction thereof as a correspondingly slight projection of the front edges of bolt *c* beyond the bearing surface of hub *b* will be sufficient to cause a satisfying coupling friction between bolt *c* and wheel *a*.

Figures 1 and 2 further show an embodiment of the means for transmitting and gearing down the necessary manual motion which means lead within the platen from a manipulating knob *d* to bolt *c*. The latter has rigid on its midst a lever *e* the free end of which is designed as an arcuate rack comprising two teeth, Figure 2, which may engage corresponding teeth of the short arm *f* of a two-armed lever *f*—*g* pivotally mounted in the platen and the longer arm *g* of which has hinged on it a rod *h* that terminates in the manipulating knob *d*. A spring *i* tends to draw rod *h* from its position shown in full lines to that shown in dotted lines and to rock arm *g* about its fulcrum to the right. Thereby arm *f* of lever *f*—*g* is rocked in the

same direction and acts upon lever *e* of bolt *c* so as to turn the latter about its axis, that is to a position between those shown in Figures 3 and 4. When this takes place, coupling is established between hub *b* and wheel *a*. When knob *d* is depressed, all parts, that is rod *h*, levers *f*, *g* and *e*, and bolt *c* return to initial position in which hub *b* and wheel *a* are uncoupled from one another.

In the embodiment illustrated in Figures 5 and 6 two cylindrical bolts *c*₁ and *c*₂ are provided extending in parallel to a diameter of hub *b* in suitable bores thereof. Each of the bolts *c*₁, *c*₂ has cylindrical end surfaces which in the uncoupled position of the bolt are flush with the cylindrical race surface of hub *b*. *e* denotes again the actuating levers of the bolts which levers in order to turn the bolts out of coupling position are rocked by means of a taper head *k*, Figure 6, being slid therebetween. Head *k* is mounted on the inner end of a suitable rod which on its other end carries knob *d*. A spring *l* attached to both levers *e* serves to cause turning motion of the bolts *c* into coupling position and to maintain them therein. When knob *d* is shifted and thereby the taper head *k* pushed toward hub *b*, the levers *e* will spread asunder and bring the bolts *c* to an angular position corresponding to the uncoupled state of the parts. Upon releasing knob *d* head *k* returns to initial position by the action of a spring *i* (shown in Fig. 1) and the levers *e* are then caused to approach one another by the spring *l* so that they assume coupling position again.

Figures 7 and 8 show an embodiment in which two threaded coupling bolts *c*₃ and *c*₄ are lodged in a common correspondingly threaded bore of the hub of the platen cap. Each of these bolts has fixed on it a rocking lever *e* the ends of which levers are turned toward one another and engaged again by the taper head *k* which as described can be shifted to the left and released by a spring similar to spring *i* in Fig. 1. This shifting motion of head *k* causes the levers *e* to spread asunder and to turn the bolts *c*₃, *c*₄ about their common axis, whereby their end surfaces which in the coupling position project a little beyond the cylindrical race surface of the hub are screwed back so far as to lie flush with or behind this surface. In this embodiment the end surfaces of the bolts *c* may be designed as in the other embodiments described as sections of cylindrical surfaces which in the releasing position are flush with the cylindrical surface of the hub, or these bolt ends may have a simple plain or curved surface.

In the embodiments described the coupling bolts themselves are immediately brought to contact with the race surface of the line-spacing wheel, to couple it with the platen. The principle of the invention, that is to

produce a coupling or uncoupling action by simple rotation of bolts extending transversely in the hub of the platen cap, may be realized however also, as illustrated by three 5 embodiments in Figures 9 to 12, by the bolts not forming immediately the coupling members, but acting upon special coupling pieces m of cylindrical or prismatic shape and guided in the hub of the platen cap normally 10 to the bolts, the latter having a cam portion n arranged eccentrically to their axis or being suitably curved. These cam portions n have a stroke such as to cause, when turned a slight angular amount, the coupling pieces m to move from their initial position within the race surface of the hub so as to project beyond the latter and to be urged 15 against the bearing surface of the line-spacing wheel.

20 As to be seen from the right-hand half of Figure 9 and from Figures 11 and 12, ball-shaped coupling members o may be arranged in front of the pieces m . In the embodiment shown in Figures 9 to 12 the actuation of the 25 bolt e is effected by the lever system e, f, g, h in a manner analogous to that of Figures 1 and 2. In Figure 12 the clearance shown between the hub b and line-spacing wheel a is somewhat exaggerated, to facilitate comprehension.

20 I claim:

1. In typewriters and similar machines a 35 rotatable platen, a front cap rigid thereon, a line-spacing wheel loosely mounted on said cap, at least one bolt transversely lodged in said cap, means for turning said bolt a slight amount about its longitudinal axis, said bolt being adapted when turned to couple said cap with said line-spacing wheel.

40 2. In typewriters and similar machines a rotatable platen, a front cap rigid thereon, a line-spacing wheel loosely mounted on said cap, at least one bolt transversely lodged in said cap in the plane of said wheel and 45 adapted to be turned a slight amount about its longitudinal axis, the ends of which bolt in position of rest at least lie flush with the race surface provided for said wheel on said cap, but project beyond said surface and 50 frictionally engage said wheel upon said bolt being turned, and means for turning said bolt a slight amount about its longitudinal axis.

3. In typewriters and similar machines a 55 rotatable platen, a front cap rigid thereon, a line-spacing wheel loosely mounted on said cap, at least one threaded bolt transversely lodged in a threaded bore of said cap in the plane of said wheel and adapted to be turned 60 a slight angular amount about its longitudinal axis, the ends of which bolt in position of rest at least lie flush with the race surface provided for said wheel on said cap, but project beyond said surface and frictionally 65 engage said wheel upon said bolt being

turned, and means for turning said bolt a slight amount about its longitudinal axis.

4. In typewriters and similar machines a rotatable platen, a front cap rigid thereon, a line-spacing wheel loosely mounted on said 70 cap, a bolt transversely lodged in said cap in the plane of said wheel, the ends of which bolt lie flush with and form portions of the race surface provided in said cap for said wheel, a lever rigid on said bolt, another lever pivotally 75 mounted within said platen and adapted to rock said first-named lever to turn said bolt, a manipulative rod lodged centrally in said platen and adapted to rock said other lever, and a spring adapted to maintain said levers in rocked position.

In testimony whereof I have affixed my signature.

HANS LUCE.
